UNITED STATES PATENT OFFICE

2,277,026

WRENCH

Carlos Saucedo, El Paso, Tex.

Application July 8, 1940, Serial No. 344,441

1 Claim. (Cl. 81—114)

This invention relates to wrenches, and its general object is to provide a wrench that is primarily designed for applying and removing notched ring packing nuts, particularly those of door closers of the hydraulic type, the wrench being adjustable to fit nuts of various sizes and is therefore capable of performing the functions and taking the place of all of a great number of wrenches and like tools, now employed by mechanics engaged in adjusting and replacing door and like closers, and in a more efficient manner.

It might be mentioned that there are more than twenty different types and sizes of closer packing nuts now in general use, and a different wrench is now required for each size, while my wrench will fit any type and size, consequently the advantages thereof will be obvious.

A further object is to provide a wrench that is not only capable of applying and removing packing nuts, in an easy and expeditious manner, and includes adjustable jaws for that purpose, but the jaws are interchangeable with penetrating toothed jaws for removing damaged packing and the like.

Another object is to provide a wrench of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a side elevation of the wrench which forms the subject matter of the present invention.

Figure 2 is a longitudinal sectional view taken therethrough.

Figure 3 is a sectional view taken approximately on line 3—3 of Figure 2, looking in the direction of the arrows.

Figure 4 is a view taken approximately on line 4—4 of Figure 2, looking in the direction of the arrows.

Figure 5 is a front view of one of the nut receiving jaws.

Figure 6 is a side view thereof.

Figure 7 is a front view of one of the packing removing jaws.

Figure 8 is a side view thereof.

Referring to the drawing in detail, it will be

noted that my wrench includes a hollow cylindrical body 1 having diametrically opposed flat faces 2 extending longitudinally of the outer surface thereof for a portion of its length and from substantially midway its ends, as clearly shown in Figure 2. The body is also provided with registering openings adjacent one of its ends for the purpose of receiving a rod 3 providing a handle for rotating the wrench, as will be apparent.

Extending longitudinally of the body from its opposite end, are diametrically opposed slots 4 that are aligned with the flat faces and the inner end walls of the slots are shaped to provide substantially V-shaped tongues 5 that receive like shaped notched ends of a pair of companion jaws 6 which are rockably mounted on the tongues for movement in the slots to be adjusted toward and away from each other, for a purpose which will be later described.

The inner and outer faces of the jaws are curved transversely, while the side faces are flat for wiping engagement with the side walls of the slots and the jaws are tapered outwardly toward their outer ends to increase the thickness thereof toward their inner faces. The jaws are of a length to extend outwardly beyond the body, as clearly shown in Figure 2, and formed on the outer ends of the jaws are lugs 7 which extend from the inner edges thereof, and each lug has formed thereon a square cornered tooth 8 for the purpose of being received within the notches of a ring type packing nut for applying and removing the same, as will be apparent.

The jaws are held associated with the body, by leaf springs 9 that have one of their ends riveted or otherwise secured to the body adjacent to the inner ends of the flat faces 2, for disposal of the springs along said faces, as best shown in Figure 2, and the jaws are secured to the opposite ends of the springs by screws 10 having serrated heads to facilitate application and removal thereof with respect to the jaws, without the use of tools.

The outer end portions of the springs are outwardly flared for normally urging the jaws away from each other, and in order to move the jaws toward each other, I provide a sleeve 11 slidably and rotatably mounted on the body 1 for disposal in wiping engagement with the springs, as clearly shown in Figure 2. The sleeve 11 is guided in its movement by a set screw 12 threaded in the body and with its head disposed within a slot 13 disposed at an inclination circumferentially of the sleeve, as best shown in Figure 1. By that

construction, it will be obvious that upon rotating the sleeve in the direction of the jaws, the wiping engagement of the sleeve against the springs 9 will adjust the jaws toward each other and a reverse movement of the sleeve will allow the springs to adjust the jaws away from each other.

In order to facilitate movement of the sleeve, while gripping the handle 3, I provide ribs 14 formed on and extending longitudinally thereof from its end adjacent to the handle and for a portion of its length, the ribs being disposed in equi-distantly spaced relation with respect to each other, to provide thumb and finger receiving spaces between the same, as will be apparent upon inspection of Figure 1.

It is believed that the use of my tool will be obvious, but it might be mentioned that in applying and removing a packing nut with respect to the closure cap of a door closer the tool is positioned in a manner for disposing the operating or crank shaft of the closer within the body 1, thence the jaws are adjusted to a position so that the teeth 8 can be inserted within the notches of the nut, for threading or unthreading the same, into or out of use.

Extreme difficulty is often experienced in removing packing especially if it is damaged, from about the operating shaft, and for that purpose I provide a pair of jaws 15 of the type shown in Figures 7 and 8. These jaws are identical with the jaws 6 with the exception that each lug 16 thereof has a pair of claw like teeth 17 formed thereon, so that when the jaws 15 are positioned within the slots 4 of the body, my wrench is converted to what may be termed a reaming tool for removing broken or otherwise damaged packing, as will be apparent. It will be obvious that the jaws 6 and 15 are readily interchangeable, and the change can be made with minimum effort and without the use of tools, due to the use of

the serrated headed screws 10, yet casual removal or displacement of the jaws is practically impossible.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A wrench for applying and removing notched ring packing nuts into and out of use and comprising a hollow cylindrical body having diametrically opposed flat faces on its outer surface and extending longitudinally thereof for a portion of its length, said body having diametrically opposed slots extending longitudinally thereof from one end to the flat faces, substantially V-shaped tongues formed on the inner ends of the slots, toothed jaws mounted in the slots and being notched to provide seats fitting and receiving the tongues therein for rocking movement of the jaws toward and away from each other, leaf spring having one of their ends secured to the flat faces and extending along the length thereof, said springs having their opposite end portions outwardly flared from the body and detachably secured to the jaws for normally urging the latter away from each other, a sleeve slidably mounted on the body and engaged with the springs for urging the jaws toward each other, said sleeve having an inclined slot disposed circumferentially thereof, a set screw secured to the body and mounted in the slot of the sleeve for guiding the sleeve in a spiral path about the body, ribs formed on and extending longitudinally of the sleeve to facilitate movement thereof, and a handle detachably secured to the body.

CARLOS SAUCEDO.
